ABSTRACT OF THE DISCLOSURE

This disclosure relates to a stable, creamy-foam shampoo comprising a tertiary amine oxide, a higher alkyl betaine or sulfobetaine and a soap in the ratio of 2:1:1, respectively.

This application is a continuation of copending application Ser. No. 816,395, filed Apr. 15, 1969, now abandoned.

The present invention relates to a clear aqueous, high-lathering shampoo composition capable of simultaneously conditioning and cleansing hair.

The formulation of shampoo for human hair is a specialized field and involves many considerations including stability and homogeneity of the product, its foaming action, and most important its ability to cleanse without diminishing the natural lustre of the hair. Soap-containing shampoos in the past have had the disadvantage of dulling the hair due to the precipitation thereon of lime and magnesium soap or the like, especially in hard water which also reduces the foaming action of the shampoo. This has largely been overcome by the substitution of synthetic organic detergents for the soap. However, many synthetic detergents tend to remove the natural oils from the hair, leaving it dry and difficult to manage. A variety of conditioning agents have been added in an attempt to overcome the detrimental effects of natural oil loss and to improve manageability of the hair. The presence of said conditioning agents have had the disadvantage of adversely affecting the foaming action of the shampoo, whereby the foam volume and/or foam stability were insufficient to effect adequate cleansing of the hair. In addition, the conditioning action of aforesaid agents were in many instances inadequate and it was necessary to utilize the additional step of rinsing with a conditioning composition.

Accordingly, it is an object of the invention to provide a high-lathering shampoo with stable, creamy foam in the presence of hair soil.

Another object is to provide a shampoo which leaves the hair conditioned, i.e. lustrous, smooth and manageable.

It has now been found that soap can be combined with a tertiary amine oxide and a higher alkyl betaine or sulfobetaine in an alkaline aqueous medium to yield a cleansing and conditioning shampoo having high and stable foaming capabilities.

Soaps utilized in the composition include the water soluble salts of higher fatty acids of naturally occurring vegetable or animal fats and oils. Examples are sodium, potassium, ammonium, monoethanolamine, diethanolamine, triethanolamine salts, morpholine, diglycolamine, etc. of fatty acids occurring in coconut oil, soy bean oil, castor oil, tallow, or synthetically produced fatty acids. The acid portion of the soap is advantageously that of a fatty acid such as lauric, myristic, stearic, oleic, elaidic, isostearic, palmitic, undecylenic, tridecylenic, penta-decylenic or other saturated or unsaturated fatty acid

2

of 11 to 18 carbon atoms. Soaps of dicarboxylic acids may also be used such as the soaps of dimerized linoleic acid. Soaps of such other higher molecular weight acids such as rosin or tall oil acids, e.g. abietic acid, may also be employed. Specific examples include triethanolamine myristate, triethanolamine cocoate, potassium isostearate, potassium myristate and the like. The soap functions as an opacifier and thickener and contributes some conditioning properties to the instant composition. Since fatty acids are a natural ingredient of the skin, the usefulness of soap for cosmetic purposes as an ingredient of a shampoo is desirable.

The water-soluble tertiary amine oxide which constitutes the major ingredient of this composition may be represented by the general formula: $R_1 R_2 R_3 N \rightarrow O$ wherein R_1 is a higher alkyl radical having from 10 to 18 carbon atoms, such as lauryl, decyl, cetyl, oleyl, stearyl, hexadecyl or an amide substituted group, such as

$RCONH(CH_3)_n$

where RCO is a long chain alkanoyl radical and n is a small whole number; R_2 and R_3 are each lower alkyl radical such as methyl, ethyl, propyl or a substituted lower alkyl radical such as hydroxyethyl, hydroxyethoxyethyl, hydroxy polyethoxyethyl etc. Examples of suitable tertiary amine oxides include lauryl dimethyl amine oxide, coconut dimethylamine oxide, dodecyl dimethyl amine oxide,

and the like. The tertiary nitrogen may also be in the form of a cyclic compound such as cocoyl morpholine oxide, cocoyl imidazoline oxide, etc.

The higher alkyl betaine or sulfobetaine utilized in the instant invention renders the soap and tertiary amine oxide compatible and is per se mildly antibacterial. The betaines may be represented by the following structural formula:

wherein R_1 is a high molecular alkyl radical having from 10–18 carbon atoms or the amido radical $RCONH(CH_2)_3$ wherein R is a higher alkyl radical, R_2 and R_3 are each alkyl radicals having from about 1 to 3 carbon atoms, R_4 is an alkylene or hydroxyalkylene radical having from 1 to 4 carbon atoms, and X is an anion selected from the group consisting of SO_3^- and COO^- radicals. R_1 and R may be a mixture of a high molecular alkyl radical and may contain one or more intermediate linkages such as ether or polyether linkages or non-functional substituents such as hydroxyl or halogen radicals which do not affect the hydrophobic character of the radical. The ionic neutrality of the betaines over a wide pH range permits both foaming and adsorption thereof from the washing solution. Examples of betaines useful herein include the high alkyl betaines such as coco dimethyl carboxymethyl betaine, lauryl dimethyl carboxymethyl betaine, lauryl dimethyl alpha-carboxy-ethyl betaine, cetyl dimethyl carboxymethyl betaine, lauryl bis-(2 hydroxyethyl) carboxymethyl betaine, stearyl bis-(2 hydroxypropyl) carboxymethyl betaine, oleyl dimethyl gamma-carboxy-propyl betaine, lauryl bis-(2 hydroxypropyl) alphacarboxyethyl betaine, etc. The sulfobetaines may be represented by coco dimethyl sulfopropyl betaine, stearyl dimethyl sulfopropyl betaine, lauryl bis-(2 hydroxyethyl) sulfopropyl betaine and the like, amido betaines and amidosulfobetaines, wherein the $RCONH(CH_2)_3$ radical is attached

to the nitrogen atom of the betaine are also useful in this invention. It is sometimes preferable to use the sulfo-betaine because of their better solubility and compatibility with synthetic detergents, wherein the betaines are desirable in the preparations of an opaque composition because of their thickening properties.

The mixture of higher alkyl betaine, soap and tertiary amine oxide should be suitably proportioned at proper pH values in an aqueous solution to yield foaming cleansing compositions which yield a strong adsorption onto hair, scalp and skin. By suitably selecting the ingredients, clear aqueous solutions with low cloud points are obtainable at alkaline pH, preferably at pH 8-9. Although the proportions of ingredients can be varied over a wide range, it is desirable that the sum of amine oxide plus betaine should be greater than the amount of soap, and the preferred ratio is 2 parts amine oxide: 1 part betaine: 1 part soap. In general, the tertiary amine oxide ingredient constitutes the major detergent in the composition in amounts ranging from 5% to 40% and preferably 10% to 20% by weight of the total. The amount of the betaine ingredient should be sufficient to effect compatibility between the tertiary amine oxide and the soap, usually about 6% and preferably about one half the amine oxide content, and more specifically about 5% to 10% by weight of the total composition. The amount of soap is less than the sum of the amine oxide and the betaine, usually about 6% and preferably one half of the amine oxide content, and more specifically about 5% to 10% by weight of the total product.

Formulations embraced by this invention are stable, homogeneous aqueous shampoos which lather properly. These compositions have the dual function of washing and conditioning the hair, leaving the hair soft and more manageable after shampooing. The need for frequent combing is minimized and the act of combing the hair is accomplished with greater facility due to the elimination of tangled hair. The hair is rendered significantly anti-static and exhibits good sheen or luster and curl retention. Other important advantages include a desirable modification of the foaming power so that there is achieved superior foam volume and stability in the presence of fatty acid soaps.

Foam tests on prototype hair conditioning shampoos have indicated that the foam stabilization contribution of alkanolamide so clearly beneficial in anionic-based shampoos, is not needed in the betaine-amine oxide-fatty acid soap compositions. Both foam volumes and foam consistencies of these novel compositions are superior to prior art formulations as evidenced by a higher volume of foam which was more stable, and slower to break down or drain out of the hair and scalp. In addition, other soap-containing shampoos are more susceptible to the effects of hard water, rendering the instant products more versatile under myriad conditions. The unusual foam stability of the amine oxide and betaine in the presence of soap renders these ternary formulations useful as soap bars and as bubble bath compositions with foam which is not destroyed by the use of conventional bath soap.

The compatibility exhibited by the betaine, soap and amine oxide ingredients, and the excellent protein adsorption of the betaine-amine oxide-soap complex at alkaline pH render these formulations particularly useful as conditioning shampoos. This is unexpected since prior art formulations containing anionic surfactants including soap and alkanolamides do not leave the hair conditioned and do not give evidence of any deposition and residual conditioning surfactants as is shown by the instant compositions, as demonstrated by the substantive deposition of Rubine W. S. dye by the shampooed and rinsed hair. Normally, substrate such as hair will not retain Rubine W. S. dye, a water-soluble anionic dye, unless first treated with cationic surfactants. However, it has now been found that untreated hair shampooed with the instant composition does retain the Rubine dye; illustrating the effective

deposition of conditioning surfactants thereon. This substantivity can be exploited in the formulation of hair coloring shampoos by the addition of direct dyes and polyethylen imine to the instant compositions.

5 Various adjuvant materials may be added to these foaming, aqueous, detergent compositions such as small amounts of viscosity builders and conditioning agents inclusive of gums, hydroxypropyl methyl cellulose and alkanolamides such as lauric myristic diethanolamide, 10 monoalkanolamides, isopropanolamides. Other ingredients may include alkaline or acid buffers to aid in the adjustment and maintenance of the desired pH of the finished product such as borax, various inorganic water-soluble phosphates, sodium hydroxide, citric acid, etc. 15 Other additions include optical brighteners, bleaches, germicides, fungicides, bactericides, colorants, perfumes, etc. in minor amounts which do not interfere with the conditioning properties of the composition.

In the manufacture of the shampoo in aqueous forms, the soap component may be prepared in advance or in situ by dissolving the soap fatty acid in warm amine oxide plus betaine or sulfobetaine. The neutralizing base such as triethanolamine, potassium hydroxide or the like is added until the pH is sufficiently alkaline, preferably 8-9. The resultant solutions are clear, moderately viscous shampoos and retain their clarity when cooled to 34° F. at pH's above 8.3. At pH's below 8.5 it has been found that the amine oxide and the soap are particularly inclined to precipitate, but the precipitation is definitely retarded by the presence of the betaine or sulfobetaine component.

The following specific examples are further illustrative of the nature of the present invention, and it is to be understood that the invention is not limited thereto. All parts are by weight unless otherwise indicated.

EXAMPLE 1

Ingredients:

40	Lauryl dimethyl amine oxide	12.0%.
	Coco sulfobetaine ¹	6.0%.
	Triethanolamine myristate	6.0%.
	Triethanolamine	To pH 8.0.
	Perfume	0.3%.
	Water	To 100%.

15 ${}^1\text{F}$ ormula:

The above ingredients are mixed together with agitation yielding a clear moderately viscous solution particularly useful as a high foaming shampoo.

EXAMPLE II

55 In lieu of the triethanolamine myristate ingredient of Example I, 4% isostearic acid is added to a warm solution of the amine oxide and sulfobetaine and sufficient triethanolamine is used to obtain a pH of 8.6. This composition remains clear when cooled to 34° F. The resultant product is a superior, clear, foaming, conditioning shampoo.

EXAMPLE III

To the composition of Example II is added 3.0% lauric myristic diethanolamide. This composition is more viscous than the solutions of Examples I and II, and remains clear when cooled to 34° F. This shampoo product is found to lather profusely and to wash and condition hair.

In addition to the usual and conventional soaps, as described above, there may also be employed other types of fatty carboxylates such as the (1) N-alkanoyl sarcosinates e.g.

5

wherein R is e.g. C₁₀ to C₂₀ (decyl, dodecyl, tetradecyl, hexadecyl, octadecyl, eicosyl, etc.); R¹ is hydrogen, alkyl or cycloalkyl e.g. methyl, ethyl, propyl, hexyl, octyl, cyclohexyl, cyclopentyl substituted cyclohexyls, etc.; x is 1 to 4 and M is a conventional cation, e.g., Na⁺, K⁺ and NH₄⁺; (2) compounds of the type

wherein R₁ is alkyl or alkaryl of e.g. C₈ to C₂₀, m is 2 or 3, n is 1 to 50 and preferably 1 to 10 and t is 1, 2 or 3; M is a conventional cation e.g. Na⁺, K⁺ NH₄⁺,

etc.

Although the present invention has been described with reference to particular embodiments and examples it will be apparent to those skilled in the art that variations and modifications of this invention can be made and that equivalents can be substituted therefor without departing from the principles and true spirit of the invention.

I claim:

1. A clear, aqueous, high-lathering shampoo composition for simultaneously cleansing and conditioning hair in a single operation which consists essentially of 5% to 20% by weight of a higher alkyl betaine having the structural formula

wherein R₁ is C₁₀-C₁₈ alkyl or C₁₀-C₁₈ alkyl amidopropyl, R₂ and R₃ are each alkyl or hydroxyalkyl radicals having from about 1 to 3 carbon atoms, R₄ is an alkylene or hydroxyalkylene radical having from 1 to 4 carbons, and X is an anion selected from the group consisting of SO₃⁼ and CO₂⁼; 10% to 20% by weight of a higher alkyl amine oxide having the general formula R₁R₂R₃N⁺O where R₁ is C₁₀-C₁₈ alkyl or C₁₀-C₁₈ alkyl amidopropyl and R₂ and R₃ are each selected from the group consisting of C₁-C₃ alkyl, C₁-C₃ hydroxyalkyl and C₁-C₃ hydroxyalkyloxyalkyl or R₂ and R₃ together with the amino nitrogen form a morpholino or imidazole group; from 5% to 20% by weight of a water-soluble soap selected from the group consisting of salts of a saturated C₁₁-C₁₈ fatty

6

acid; said salt being selected from the group consisting of sodium, potassium, ammonium, monoethanolamine, diethanolamine, triethanolamine, diglycolamine, and morpholine; and the balance being water; said shampoo having a pH of from 8 to 8.6.

5 2. A composition in accordance with claim 1 wherein the amine oxide is lauryl dimethylamine oxide.

3. A composition in accordance with claim 1 wherein the soap is a triethanolamine soap.

10 4. A composition in accordance with claim 1 wherein said higher alkyl betaine is present in an amount of 5% to 10% by weight, said soap is present in an amount of 5% to 10% by weight, and the sum of said betaine and said amine oxide being greater than the amount of soap.

15 5. The composition in accordance with claim 4 wherein in the ratio of amine oxide:betaine:soap is 2:1:1.

6. A composition in accordance with claim 1 wherein the betaine ingredient is cocosulfobetaine.

20 7. A composition in accordance with claim 6 wherein the amine oxide is lauryl dimethylamine oxide and the soap is a triethanolamine soap.
